NURSING BOTTLE APPLIANCE
Robert A. Johnson, 206 Juniper Ave.,
South San Francisco, Calif.
Filed May 28, 1963, Ser. No. 283,905
6 Claims. (Cl. 215—11)

This invention relates to a nursing bottle appliance that entertains an infant by providing a pleasing visual sensation as the infant drinks fluid from the bottle but does not interfere with filling or cleaning the bottle.

The present invention contemplates generally a staff that is pivotally attached to the bottle near the lower end thereof. The staff on its unattached end is provided with a brightly colored ornament of a type that will retain the infant's attention while nursing and is shaped to support the ornament within view of the nursing infant. The staff is formed so that it is held in the viewing or extended position by its own weight.

A feature and advantage of the present invention is that the staff can be made of resilient material so as to cause the ornament to oscillate or jingle when the nursing infant moves it about. This action in addition to holding the infant's attention to the bottle and the ornament, promotes eye exercise which fosters early development of the infant's eyes.

Another feature and advantage is that the pivotal mounting of the staff permits placement of the bottle on a table or similar flat surface for filling without removal of the appliance from the bottle.

Still another feature and advantage is that the staff is so shaped that when the bottle is in the inverted nursing or feeding position the center of gravity of the staff is disposed relative to the pivotal mounting of the shaft to cause the staff to remain in its operative or extended position.

A further feature and advantage resides in the fact that the appliance can be readily removed from a nursing bottle while the bottle is cleaned and sterilized. Ready removal is afforded by the cup-like structure of the appliance which forms a concavity for receiving the bottom of a nursing bottle.

Other objects, features and advantages of the present invention will be more apparent after referring to the following specification and attached drawings in which:

FIG. 1 is a cross sectional view of a nursing bottle equipped with an appliance of the present invention and in which the staff in extended position is shown in solid lines and the staff in a folded position is shown in broken lines;

FIG. 2 is a cross sectional view taken along line 2—2 of FIG. 1;

FIG. 3 is an elevational view of the base of the appliance of my invention taken along line 3—3 of FIG. 1;

FIG. 4 is a cross sectional elevation view taken along line 4—4 of FIG. 2; and

FIG. 5 is a view similar to FIG. 3 showing a modification of my invention.

Referring more particularly to the drawings, a conventional nursing bottle A is provided at its bottom end with a cup-like base member B that has a staff C pivotally mounted thereto. At the free or unmounted end of staff C is affixed a brightly colored ornament D. With staff C in the extended position, the position depicted by the solid lines of FIG. 1, ornament D is visible to a baby from the top or nipple end of nursing bottle A.

Base member B is formed with a concavity or opening 12 shaped to receive the bottom end of bottle A. The inner walls of opening 12 can be shaped to frictionally engage the side of bottle A. Alternately, if base B is constructed of resilient material such as plastic, projec-

2

tions 14 are formed on the inner wall of opening 12 to frictionally engage bottle A when the bottle is inserted into opening 12. Base B is provided with a flat bottom formed by a flange 16 extending around the periphery 5 thereof so that the bottle inserted into opening 12 will be supported in a vertical position for filling.

Extending outwardly from base B are spaced apart projections 18 and 20 that are suitably drilled to receive a shaft 22 therebetween. Below shaft 22 and in axial alignment therewith, flange 16 is formed with a notch 24. Notch 24 is shaped to receive staff C therein when the staff is in an extended position.

Staff C is mounted to shaft 22 by means of a suitable bearing member 26 formed to pivotally fit onto the shaft. 15 The staff is affixed in any suitable manner to bearing member 26 to permit pivotal movement from an extended position to a folded position. Staff C is formed with a straight portion 28 adjacent bearing member 26 and then with a curved or arcuate portion 30, so that when the staff is in an extended position, the arcuate portion extends into a cylindrical volume that would be formed by an axial extension of the exterior surface of bottle A. Staff C is formed at the end remote from bearing member 26 with a straight portion 32 shaped so that the unattached 25 end of the staff is visible from the top end of bottle A.

At the unattached end of staff C on straight portion 32 is affixed a brilliantly colored ornament D. Ornament D can be formed with a plurality of petal-shaped members 34 of cloth or plastic, or be of any other suitable 30 form.

In operation, the bottom end of bottle A is inserted into opening 12 of base member B. Frictional engagement of the bottle by protuberances 14 retains the base member onto the bottle. The bottle may now be placed 35 on a table in a vertical position for filling because staff C can be readily pivoted about shaft 22 to the position shown by broken lines of FIG. 1. After the bottle has been filled and the cover nipple inserted thereon, it can 40 be given to a baby; when the bottle is held in an inverted nursing or feeding position, staff C will pivot to the extended position shown in solid lines in FIG. 1. The staff will be held in that position by its weight since, when the bottle is inverted, the center of gravity of the staff acts 45 on the side of shaft 22 to retain the staff in its extended position. With a staff shaped as that of FIG. 1, bottle A can be inverted to at least 60° relative to a horizontal plane and the staff will still be held in its extended position by its weight. Other configurations for staff C to 50 assure the proper location of the shaft center of gravity relative to the pivot point at shaft 22 will be obvious to those skilled in the art.

Because staff C can be made of thin, resilient material, such as spring steel wire, ornament D will experience 55 oscillation or jiggling when the bottle is moved slightly by the infant. The child is enticed to follow the ornament with its eyes due to the bright color and movement of the ornament. This exercises and causes early development of the eye muscles and is thought to encourage 60 the child to take more food.

Referring now to FIG. 5, a modification of my invention is shown in which flange 16 is provided with a notch 24' that is formed to releasably lock the shaft in the notch. Notch 24' is formed with a width substantially equal to the diameter of staff C at straight portion 28 so that the walls of notch 24' frictionally engage staff C. This modification provides positive locking of staff C in the extended position but enables placement of bottle A on a flat surface because the locking action of notch 24' is releasable.

While two embodiments of my invention have been shown and described, it will be apparent that other adap-

tations and modifications can be made without departing from the spirit and scope of the invention.

I claim:

1. An appliance for an infant nursing bottle comprising a staff, means for mounting said staff at one end thereof to the bottle for pivotal movement between a folded position and an extended position, and an ornament affixed to the other end of the staff, said staff being formed of resilient material and defining a generally arcuate shape so that the weight of the staff acts on a side of the pivotally mounted staff end to maintain the staff in the extended position when the bottle is in a slanted inserted infant nursing position.

2. A device for an infant's nursing bottle comprising a cup-like member for receiving the bottom of the bottle, a pair of spaced apart projections on the exterior of said cup-like member, a staff pivotally mounted at one end thereof between said projections, and an ornament attached to said staff at the unmounted end thereof, said staff defining a generally arcuate shape and being adapted to be held in an extended position by the weight thereof when the bottle is in a nursing position to support said ornament in view of the nursing infant.

3. An appliance for an infant nursing bottle comprising a staff, means for attaching one end of said staff to the bottle for pivotal movement between an extended position and a folded position, and an ornament affixed to said staff remote from the attached end, said staff being formed so that it is maintained in the extended position by its weight when the bottle is held in an inverted slanted position and the ornament is visible to the user of the bottle, said staff being adapted for movement to the folded position to permit placement of the bottle in an upright position.

4. An appliance for an infant nursing bottle comprising a base having a concavity for receiving the bottle in frictional engagement and a substantially flat bottom adapted to support the base and bottle in an upstanding position, a pair of spaced apart projections on said base, a shaft mounted between said projections in a plane substantially parallel with the bottom of said base, a staff

5 mounted by one end thereof for pivotal movement between a folded position and an extended position around said shaft, and an ornament affixed to the non-mounted end of said staff, said staff being formed of resilient material and defining a generally arcuate shape having a center of gravity relative to said bottle to cause said staff to maintain the extended position and to resist pivotal movement toward the folded position when said bottle is placed in the infant feeding position.

10 5. An appliance for an infant nursing bottle comprising a base having a concavity for receiving the bottle in frictional engagement, a flange surrounding said base adapted to support the base and bottle in an upstanding position, a pair of spaced apart projections on said base, a shaft mounted between said projections in a plane substantially parallel with the bottom of said base, a notch defined by said flange in substantial axial alignment with said shaft, a staff mounted by one end thereof for pivotal movement around said shaft between a folded position 20 in which the staff is pivoted to permit placement of said base flange on a flat surface and an extended position in which said shaft is disposed in said notch, and an ornament affixed to the non-mounted end of said staff, said staff being formed of resilient material and defining a generally arcuate shape having a center of gravity relative to said bottle to cause said staff to maintain the extended position and to resist pivotal movement toward the folded position when said bottle is placed in the infant feeding position.

30 6. The invention of claim 5 in combination with means to releasably lock said shaft in said notch.
